UNITED STATES PATENT OFFICE.

GOODWIN B. SMITH, OF PHILADELPHIA, PENNSYLVANIA.

SUPPORTER OF CATAMENIAL SACKS OR NAPKINS.

1,383,529.

Specification of Letters Patent. Patented Aug. 23, 1921.

Application filed March 15, 1921. Serial No. 452,419.

To all whom it may concern:

Be it known that I, GOODWIN B. SMITH, a citizen of the United States, residing at Philadelphia, in the county of Philadelphia and State of Pennsylvania, have invented certain new and useful Improvements in Supporters of Catamenial Sacks or Napkins, of which the following is a specification.

10 My invention relates to supporters for catamenial sacks, napkins, or the like.

In accordance with the present invention, a device of the above mentioned character is provided, which embodies a preferably closed band to encircle the waist, which is highly elastic, and may be passed upwardly over the hips of the wearer, to position the same. I also contemplate making the device with the ends of the band detachably connected. The band of the device is formed of elastic webbing, with which is interwoven a loose corrugated strip, forming corrugations, flutes or cells upon the side or sides of the webbing. These cells 25 retain the webbing spaced from the body of the wearer, thereby prolonging the life of the webbing, insuring coolness, comfort, and perfect ventilation at all times. The garment is of great durability, strength, lightness and beauty. Owing to the arched shape of the corrugations or cells, they are adapted to retain their shape to a considerable extent.

In the accompanying drawings, forming 35 a part of this invention, and in which like numerals are employed to designate like parts throughout the same,

Figure 1 is a perspective view of a supporter or garment embodying my invention,

40 Fig. 2 is a bottom plan view, with parts folded out, and

Fig. 3 is a detail section, taken on line 3—3 of Fig. 1.

45 In the drawings, wherein for the purpose of illustration is shown a preferred embodiment of my invention, the numeral 5 designates a waist band, which is preferably closed, by which is meant that its ends are 50 permanently secured together. This band is highly elastic, and comprises an elastic webbing 6, preferably a cotton webbing, embodying longitudinal elastic threads and transverse cotton threads covering the same.

55 The elastic webbing is provided at spaced intervals with transverse openings 7, formed

in the cotton covering, for the reception of the warp threads of a loose corrugated or fluted spacing fabric strip 8, the woof threads of which are woven close up to the 60 woof threads of the webbing. The loose corrugated strip is preferably formed of silk or other like material which is soft and hence very comfortable. This strip, thus interwoven with the webbing, produces 65 spaced transverse corrugations or cells 9, upon opposite sides of the webbing. These corrugations project laterally beyond the webbing a substantial distance, are tubular, and have their ends open. The inner set of 70 corrugations function to retain the webbing spaced from the body, thereby prolonging the life of the same, also insuring comfort, coolness, and ventilation. The arch shape of the corrugations enables them to retain 75 their shape to a considerable extent. The corrugations or cells extend beyond the longitudinal edges of the webbing, thereby preventing such edges contacting with the body.

80 The ends of the band extend downwardly slightly, at the front of the supporter, and these ends are suitably secured together. A depending element or tab 10 has its upper end arranged over the ends of the band, and a section of cloth 11 is placed over this end, these elements being stitched together, at 12. The element 10 is preferably formed of the same material as the band 5, as shown. A section of cloth 13 is stitched 85 to the lower end of the element 10, to which the sack or napkin may be secured by a safety pin 13, carried by a flexible element 14, attached to the band 5, as shown.

90 At the rear of the band, a depending element or tab 15 is provided, the upper end of which is arranged upon the outer side of the band, with a section of cloth 15' thereon, the elements being stitched together, at 16. The tab 15 is preferably formed of the 95 same material as the band 5. At its lower end, the tab 15 has a piece of cloth 17, stitched thereto, to which the opposite end of the sack or napkin is secured by a safety pin 18, carried by a flexible element 19, secured to the band 5, as shown.

100 In view of the foregoing description, it is thought that the use of the supporter is obvious, and that no further explanation is necessary.

110 It is to be understood that the form of my invention herewith shown and described

is to be taken as a preferred example of the same, and that various changes in the shape, size, and arrangement of parts may be resorted to without departing from the spirit of the invention or the scope of the subjoined claims.

Having thus described my invention, I claim:

1. A supporter of a catamenial sack or napkin, comprising a waist band, said band embodying an elastic webbing and a corrugated strip woven therewith, said strip forming arched cells extending laterally beyond the webbing for a substantial distance, said cells holding the webbing spaced from the body, and supporting elements carried by the band.
2. A supporter of a catamenial sack or napkin, comprising a waist band, said band embodying an elastic webbing, a section of non-elastic fabric woven transversely through the webbing and forming tubular flutes at spaced intervals through substantially the entire length of the webbing.
3. A supporter of a catamenial sack or napkin, comprising a waist band, said band embodying an elastic webbing having spaced arched cells secured to the webbing at spaced intervals, said arched cells extending laterally beyond the webbing and serving to hold the webbing spaced from the body.
4. A supporter of a catamenial sack or

napkin, comprising a waist band, said band embodying an elastic webbing having transversely extending arched cells secured to the webbing at spaced intervals, said arched cells being tubular and extending beyond the edges of the webbing.

5. A supporter of a catamenial sack or napkin, comprising a waist band, and a continuous fabric strip interwoven therewith at spaced intervals, said strip forming spaced tubular flutes extending transversely of the webbing, said flutes being adapted to retain their shape to a considerable extent by virtue of their transverse curvature.

6. A supporter, comprising a band to encircle a portion of the body, said band embodying an elastic webbing, and a section of non-elastic fabric woven through the webbing at spaced intervals, forming tubular flutes adapted to retain their shape to a considerable extent.

7. A supporter, comprising a band to encircle a portion of the body, said band embodying an elastic webbing, and a section of non-elastic fabric woven through the webbing at spaced intervals and extending upon opposite sides thereof forming tubular flutes arranged upon opposite sides of the webbing.

In testimony whereof I affix my signature,

GOODWIN B. SMITH.
